UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,251,475.

Specification of Letters Patent.

Patented Jan. 1, 1918.

Application filed December 13, 1916. Serial No. 136,626.

To all whom it may concern:

Be it known that I, HENRY P. CLAUSEN, a citizen of the United States, residing at Mount Vernon, in the county of Westchester 5 and State of New York, have invented certain new and useful Improvements in Telephone-Exchange Systems, of which the following is a full, clear, concise, and exact description.

10 This invention relates to telephone exchange systems, and particularly to methods of and apparatus for making peg counts in an automatic exchange.

An object of the invention is to provide 15 for the accurate and as nearly instantaneous as possible count of the number of calls being handled by a telephone exchange system at any one time, whereby certain data may be gathered with the least amount of 20 effort.

Briefly stated this object is accomplished 25 by automatically and successively bringing a recording device into association with the apparatus of a system and making it responsive to the busy condition of such apparatus.

A further object of this invention is to provide means for automatically counting the number of calls handled over a given 30 length of time and making a record on a single chart or a number of charts which by a later scrutinization will reveal the conditions of traffic.

Previously made peg counts have revealed 35 certain conditions which have been recognized and heeded in the design and construction of new systems; for instance, one fact well established by such methods is that ten line finder switches and ten connector 40 switches are sufficient to handle the traffic initiated by or directed to a group of one hundred lines in an automatic telephone exchange.

Hence, by counting the number of line 45 finders busy and the number of connector switches busy, only one-tenth the amount of work would need be done should the total number of lines be examined with a view to counting those busy.

50 A feature of the invention is the method

of making a count and record of the various factors entering into a full and complete revelation of traffic conditions at any stated time or over any given length of time.

It will be shown in the following detailed 55 description how a count may be made of the total number of calls initiated within the exchange at any one time, the total number of calls being answered by the subscribers within an exchange at any one time or over 60 any given period of time, the total number of trunks between selectors busy at any one time or over any given period of time, the total number of lines within the exchange busy at any one time or over any given 65 period of time, the total number of incoming trunks from other exchanges busy at any one time or over any given period of time, and the total number of outgoing trunks to other exchanges busy at any one time or over 70 any given period of time.

This invention is not limited to use in an automatic exchange system, but may be applied to a manually operated system. The 75 following description will therefore also show how a count may be made of the total number of cord circuits busy at any one time, the total number of cord circuits busy within any stated period and the total number of completed connections at any time or over 80 any given period of time.

In the drawings, Figure 1 represents diagrammatically the recording device and the means whereby it is brought into association with the apparatus of which it is intended to make a record of that part which is busy; Fig. 2 is a diagrammatical representation of the organization of the automatic switches within one exchange and the manner in which the recording devices 85 shown in Fig. 1 are associated therewith; Fig. 3 represents diagrammatically the manner in which the recording device of Fig. 1 is associated with the cord circuits of a manually operated exchange; and Fig. 4 shows a 90 modification of the recording device useful in making a peg count of the total number of cord circuits busy within a given period of time.

In Fig. 1, 1 represents a terminal board 100

upon which appears a multiple of terminals connected to the apparatus to be tested. Each separate terminal, such as 2, 3 or 4, is connected to a certain point in the circuit of an automatic switch or a trunk circuit where a characteristic electrical condition denotes the fact that such switch or such trunk is busy.

The brushes B¹, B², etc., are arranged to travel over and make contact with the terminals 2, 3 and 4. A magnet SM is provided for stepping the brushes from one set of terminals to another when the test on the first set is completed, the action of this magnet being described in detail somewhat later.

Each brush such as B¹ or B² is connected to a recording magnet RM¹ or RM² which is responsive to the characteristic electrical condition denoting a busy condition of the apparatus under test. The recording magnets RM¹, etc., are arranged to control armatures such as A¹, which, in turn, actuate number wheels such as 5. Number wheel 5 is provided with raised figures in such a manner that when the chart C is pressed firmly against the periphery of the wheel 5, an impression will be left thereon. The magnet 6 is provided with an armature 7 so fashioned that in its actuated movement it presses the chart C, through the agency of rod 8, against the periphery of number wheels, such as 5. The armature 7 is also provided with a pawl which engages the teeth secured to the roller 15 whereby the chart C is moved forward one step each time the magnet 6 becomes deenergized.

The operation of the recording device may be described as follows: The hand switch H is first closed and a circuit thereupon established between ground, battery, hand switch H, magnet 9, normal contact and armature of relay 10 to ground. Magnet 9 attracts its armatures 11, 12, 13 and 14, and thereby establishes connection between the brushes B¹, B², etc., and the windings of recording magnets RM¹, RM², etc. Should the brush B¹, for instance, rest upon the terminal 2, which is connected with a busy piece of apparatus, then the recording magnet RM¹ in responding would move the number wheel 5 forward one position.

As soon as a constantly moving interrupter I of any well-known type, such as are used in telephone systems, moves around to such a position that a circuit is closed therethrough extending from ground, battery, hand switch H, winding of relay 10, the interrupter I, and thence to ground, the relay 10 is energized. The energization of relay 10 results in the movement of its armature, and the opening of the heretofore described circuit through magnet 9. Magnet 9 thereupon retracts its armatures.

A circuit is now established from ground,

the armature and alternate contact of relay 10 to a point where the circuit divides and may be traced thence in one direction through the winding of magnet SM to battery and ground, and in the other direction through the winding of relay 6 to battery and ground. Relay 6 and magnet SM thereupon attract their armatures, magnet 6 thereby causing an impression to be made on the chart C, and magnet SM causing the movement of the brushes B¹, etc., to the next set of terminals.

It should be noted that magnet SM is a diagrammatic representation of the actuating means of any well-known step-by-step type of switch, in which the successive energizations of a magnet cause several brushes to come successively into contact with a plurality of fixed terminals.

As soon as the interrupter I moves to the point where the circuit therethrough is broken, the armature of relay 10 will return to its normal position, thereby causing the deenergization of magnets 6 and SM, and the reenergization of magnet 9. Suppose at this time that brush B¹ rests upon the terminal 3 leading to a mechanism which is idle. The recording magnet RM¹, being nonresponsive to an idle condition, will leave the number wheel 5 in the position heretofore assumed, and upon the next impression being made, the same number will appear on the chart.

If each number wheel, such as 5, is originally set in such position as to record zero on the first impression, then at the end of the test the last row of figures appearing will be an indication of the number of busy mechanisms encountered by each brush respectively. The sum of these figures will be the total of the busy mechanisms. Moreover, a close scrutiny of the chart which may have been previously ruled and designated to correspond with the terminals over which the brushes are to travel, will show by the positions where the number wheel 5 was moved, just which mechanism was busy, if such information is wanted.

Referring now especially to Fig. 2, the figures designated LF¹, LF², LF³ and LF⁴ represent groups of line finder switches. The figures designated FS¹, etc., SS¹, etc., C¹, etc., represent first selectors, second selectors and connector switches, respectively. The figures designated R¹, R², R³, R⁴ and R⁵ represent recording mechanisms substantially the same as that described in Fig. 1. The recording mechanism R¹ is intended and arranged to record the number of line finders busy in the groups LF¹ and LF². The recording mechanism R² is intended and arranged to detect and record the number of connector switches busy in groups C¹ and C², and the recording

mechanism R^5 is intended and arranged to record the number of busy trunks between first selectors FS^1 and FS^3 and second selectors SS^1 and SS^3 .

5 A call initiated in the group of lines served by the line finders LF^1 will be switched to the group of first selectors FS^1 , from which the connection will be extended to a second selector, such as SS^1 or SS^3 , 10 from which it will, in turn, be extended to any one of the connector switches indicated.

If, now, a peg count is taken at any time, the records may be examined subsequently and will reveal the traffic conditions at the 15 time of the test in the following manner: A sum of the line finders busy as taken by the recording mechanisms R^1 and R^3 will indicate the number of calls initiated within the exchange at that time; the sum of the 20 connector switches found busy as recorded by the recording mechanisms R^2 and R^4 will indicate the number of calls being answered within the exchange at the given time. The record taken by the mechanism R^5 and other 25 mechanisms similarly connected to the trunk cables extending between the first and second selectors will indicate the number of such trunks busy at that time.

Should it be assumed that Fig. 2 represents only a single exchange, then the sum of the records made by R^1 and R^3 should equal the sum of the records made by R^2 and R^4 , and either one would represent the total number of lines in the exchange busy. 35 Should it be assumed that Fig. 2 represents an exchange within a system including a plurality of exchanges, then an additional record must be made of the busy incoming trunks from other offices and the busy outgoing trunks to other offices. In this case 40 the sum of the records made by R^1 , R^2 , R^3 and R^4 minus the sum of incoming and outgoing foreign office trunks would represent the number of lines within the exchange 45 which are busy. At the same time a record would be had of the traffic conditions within the foreign office trunks themselves.

Other combinations useful in the traffic department of a telephone company may 50 be made in a manner substantially the same as that described.

In Fig. 3 the brushes B^3 and B^4 are arranged to travel over and make contact with the terminals 32, 33, 34, 35, etc., and 55 form part of a recording device RD which is similar to that shown in Fig. 1.

The terminals 32 and 33 lead to the sleeve conductors 30 and 31 respectively of the answering plug AC^1 and the calling plug 60 CC^1 , respectively, of a manual telephone exchange cord circuit. The terminals 34 and 35 lead in a similar manner to plugs AC^2 and CC^2 .

The recording device RD is made respon-

sive to the well-known busy condition of 65 such cord circuits whereby a record is made of such cords as are found in use.

At the end of the test similar to that described in connection with Fig. 1 the record made by the device RD may be scrutinized 70 and a determination made of the number of cords in use, and the number of completed connections at the time the test was made.

Referring now especially to Fig. 4, this represents a modification of the recording 75 device shown in Fig. 1, and has for its object the counting of the number of cords busy over a certain interval of time. The brushes B^5 and B^6 are driven over the terminals 40, 41, 42, 43, etc., by the stepping 80 magnet SM^4 in a manner similar to that heretofore described. The resistance 44 which shunts the supervisory lamp SL^1 when the cord AC^3 is busy, is connected to 85 the terminals 40 and 41 in the following 85 manner: One terminal of resistance 44 is connected to the winding of a relay 46, and from thence through the normal contacts of its armature to the terminal 40. The other terminal of resistance 44 is connected 90 to terminal 41 and to the armature of relay 46 in parallel.

When now the brushes B^5 and B^6 are driven into association with the terminals 40 and 41, the drop of potential across the 95 resistance 44 allows a current to flow over the path leading from resistance 44, terminal 41, the brush B^6 , the relay 45, the brush B^5 , the terminal 40, the normal contacts of relay 46, the winding of relay 46 100 to the resistance 44. Current flowing over this circuit energizes relays 45 and 46. Relay 46, in attracting its armature, however, completes a locking circuit for itself through 105 its armature and alternate contact and opens the connection between the resistance 44 and the terminal 40. The relay 45 is thereby de-energized.

During the brief energization of this last 110 relay, a circuit is completed from ground, the left-hand armature and contact of relay 47, the armature and contact of relay 45, the recording magnet RM^4 to battery and thence to ground. Recording magnet RM^4 attracts 115 its armature A^4 , thus actuating the ratchet 48 and an associated number wheel to perform the function heretofore described. At the same time recording magnet RM^4 attracts another of its armatures and completes 120 a circuit from grounded battery, armature and contact of magnet RM^4 , normal contacts of the right-hand inner armature of relay 47, the winding of relay 47, the contact and armature of magnet SM^4 to ground. Relay 47 attracts its armatures and completes 125 a locking circuit for itself through ground, the armature and contact of magnet SM^4 , the winding of relay 47, the alter-

nate contact and innermost right-hand armature of relay 47, the winding of magnet SM⁴ to battery and thence to ground. Magnet SM⁴ attracts its armature and opens the circuit just described, at the same time causing the brushes B⁵ and B⁶ to move into association with the terminals 42 and 43.

If we assume that the cord AC³ were not busy, then neither relay 45 nor 46 would have responded, in which case none of the other actions would have resulted as described. However, a circuit is provided from ground, through the interrupter I⁴, the outermost right-hand armature and contact of relay 47, the winding of stepping magnet SM⁴ to battery and thence to ground, through which current for energizing the stepping magnet SM⁴ would have flowed. In this manner the brushes B⁵ and B⁶ would have been directed into association with the terminals 42 and 43.

Such a recording device as this is intended to be operated over a bank of terminals successively at intervals during a stated period of time. If, on the first movement a busy cord circuit is encountered, relay 46 would attract its armatures as described, and close a locking circuit for itself which would not be broken until the cord AC³ were restored to an idle condition. If, before this happens, the brushes B⁵ and B⁶ again passed over the terminals 40 and 41, the relay 46 will be found still in an energized condition and no second record will be made of the condition of cord AC³. If, however, during the movement the cord AC³ has become idle and has again been taken for use, the circuit will be found in the original condition and a new record made of its new use.

40 In such a manner then can the total number of cords in an exchange used over a stated interval of time be counted.

What is claimed is:

1. In a recording device, a bank of terminals, a plurality of brushes arranged to travel over and make contact with said terminals, a plurality of recording magnets associated with said brushes, each arranged to be responsive to a characteristic electrical condition which may exist on said terminals, a chart for receiving a record under control of said recording magnets, and means for successively and automatically moving said brushes into association with said terminals.

2. In a telephone exchange, line switches, means for making a peg count of traffic conditions therein, comprising a plurality of recording devices responsive to the busy condition of said line switches, and means for successively and automatically moving said recording devices into association with said switches.

3. In a telephone exchange system, line

switches, connector switches, and foreign office trunks, means for making a peg count of traffic conditions therein comprising a plurality of recording devices, said recording devices being responsive to the busy condition of such pieces of apparatus, and means for successively and automatically bringing said recording devices into association with said pieces of apparatus.

4. In a telephone exchange system, means for making a peg count of traffic conditions within a particular group of automatic switches comprising a recording device responsive to the busy condition of such switches, and means for successively and automatically bringing said recording device into electrical connection with such switches.

5. In a telephone exchange, means for making a peg count of traffic conditions within such exchange at a given time comprising a plurality of recording devices arranged in association with the organisms of said exchange and responsive to the busy condition of said organisms, and means for successively and automatically bringing said recording devices into electrical connection with the particular groups of organisms over which each of said recording devices has supervision.

6. In a telephone exchange system, means for making a peg count of traffic conditions within such system over a given period of time comprising a plurality of recording devices each responsive to the busy condition of the apparatus under count, means for preventing more than a single count of a particular piece of busy apparatus, and means for successively, repeatedly and automatically bringing said recording devices into electrical association with such apparatus.

7. In a recording device, a bank of terminals, a plurality of brushes arranged to travel over and make contact with said terminals, a plurality of recording magnets associated with said brushes and each arranged to be responsive to a characteristic electrical condition which may exist on said terminals, a chart for receiving a record under control of said recording magnets, means for successively advancing said chart, and means for successively and automatically moving said brushes into association with said terminals.

8. In a telephone exchange, connecting circuits, means for making a peg count of traffic conditions therein comprising a plurality of recording devices, said recording devices being responsive to the busy condition of said circuits, and means for successively and automatically moving said recording devices from association with one group of connecting circuits into asso-

ciation with another group of connecting circuits.

9. In a telephone exchange, telephone lines and means for interconnecting said telephone lines, means for making a peg count of traffic conditions within such system comprising a recording device responsive to the busy condition of said inter-

connecting means, and means for successively and automatically bringing said recording device into association with the units of said interconnecting means. 10

In witness whereof, I hereunto subscribe my name this 11th day of December, A. D. 1916.

HENRY P. CLAUSEN.
